UNITED STATES PATENT OFFICE.

WELLINGTON PARKER KIDDER, OF BOSTON, MASSACHUSETTS, ASSIGNOR TO THE
NOISELESS TYPEWRITER COMPANY, OF MIDDLETOWN, CONNECTICUT, A CORPO-
RATION OF CONNECTICUT.

TYPE-WRITING MACHINE.

1,194,845.

Specification of Letters Patent Patented Aug. 15, 1916.

Application filed December 15, 1910. Serial No. 597,490.

To all whom it may concern:

Be it known that I, WELLINGTON PARKER KIDDER, a citizen of the United States, residing at Boston, in the county of Suffolk and State of Massachusetts, have invented certain new and useful Improvements in Type-Writing Machines, of which the following is a full, clear, and exact description, such as will enable others skilled in the art to which it appertains to make and use the same.

This invention relates to typewriting machines, and with regard to the more specific features thereof, to ribbon mechanism therefor.

One of the objects of this invention is to provide a simple and practical ribbon mechanism for typewriting machines.

Another object is to provide improved devices of the class stated which will be simple to construct and cheap to manufacture.

A further object is to provide ribbon mechanism particularly adapted for visible typewriting machines, and which will be efficient and dependable in operation.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of many possible embodiments of my invention, Figure 1 is a longitudinal view of a typewriting machine showing such parts as are sufficient to illustrate the present invention; Fig. 2 is a perspective view of certain parts shown in Fig. 1; and Figs. 3 and 4 are diagrammatic plan views showing the relative position of the ribbon to the type and the platen when in normal and actuated position, respectively.

While the present invention is herein illustrated and described with reference to that form of typewriting machine known as the noiseless typewriter, it is of course understood that many of the features shown and hereinafter claimed are applicable to other forms of typewriting machines as well.

Similar reference characters refer to simi-

lar parts throughout the several views of the drawings.

Referring to these drawings in detail, 1 represents the base or framework of the machine, provided at each side of the rear portion with upwardly curved members 2 and 3 having a member 4 extending therebetween forming a rigid abutment or backing for a platen carriage which is adjustable fore and aft of the machine in any desired manner. This platen carriage comprises opposite end plates, one of which is denoted by the numeral 5 in Fig. 1, and carries therebetween a paper feed roller 6 and a flat platen 7, adapted to receive the printing impression, extending upwardly from which is an erasing table 8. Paper is fed between the rear of the erasing table 8 and the paper table 9 under the feed roller 6 and over the flat platen 7. The other parts of the carriage, such as the complementary paper feed rollers, indicating means and the like, are herein omitted for the sake of clearness. This carriage reciprocates from right to left in a well known manner under the action of a spring driving drum and an escapement mechanism, which are also omitted and is shiftable up and down from a normal intermediate position by the key actuated means, such as herein shown and described. This shift mechanism comprises, in brief, a roller 10, engaging a channel bar 11 on the carriage, and carried by a stud 12 mounted upon a lever 13, the upper part of which is held against transverse movement by means of a connecting member 14 supported by the frame of the machine. The lower part of the lever 13 is provided with a roller 15 engaging a cam slot 16 in a block 17 secured to the base. This cam slot 16 is substantially in the form of a reverse curve extending upwardly from right to left, as clearly shown in Fig. 2.

Intermediate the ends of the lever 13 is a pin 18 forming a pivot point for a link 19 connected with an upwardly extending arm 20 mounted on a rock shaft 21. The forward end of this rock shaft 21, or that part near the keyboard, is provided with a horizontally disposed member 22, the ends of which are adapted to be engaged, respectively, by downwardly curved hook members 23 and 24, supported from a rock shaft 25. The hook member 23 is preferably an

integral part of a key lever 26, while the hook member 24 is keyed or otherwise secured to the shaft 25, as by means of the set screw 27, as is also a second key lever 28 by means of the set screw 29. A collar 30 surrounding the shaft 25 prevents lateral movement of the key lever 26.

It will thus be seen that as the lever 26, for instance, is depressed for shifting the carriage to receive lower case characters, the hook member 23 carried thereby will operate the rock shaft 21 through the member 22 and force the lower end of the lever 13 to the right, the upper end being held against lateral movement. The cam slot 16 engaged by the roller 15 will pull the lever 13 downwardly, thereby shifting the platen carriage downwardly, while on the other hand, if it is desired to print upper case characters, the key lever 28 is depressed, which, through the hook member 24, rocks the shaft 21 in the opposite direction and the connecting parts will pull the lever 13 to the left, thereby raising the platen carriage.

25 Mounted on the upper part of the base of the machine is a type bed or plate 31, suitably grooved, as at 32, and provided with upwardly extending members 33 to prevent a lateral movement of the type carriers, only 30 one of which is herein shown, as at 34. A plate 35 coacts with the upper edge of the type carriers to prevent any upward movement thereof. A type member 36 is carried by each type carrier and is provided with a plurality of type 37, in the present instance three in number, adapted to coact with the flat platen 7. The type carrier is actuated 35 by pressure-operated mechanism of a well known character for moving the same through a limited path of travel, whereby they coact with the platen silently and without impact or concussion. This mechanism comprises, in brief, a link 38 connected with the rear end of the type carrier and a projecting lug on an oscillatory cam member 39. This cam member is provided with a slot 40 which is engaged by the roller 40 carried by a pivotally mounted lever 41, which is swung downwardly under the action of a key lever 42 connected therewith by the pull wire 43. The key levers are pivoted at 42' near the rear of the machine and are adapted to move vertically in comb members 44 and 45 and rest upon a universal bar 46 suspended from 55 arms 47 carried by a universal rock shaft 48.

As the mechanism above described forms no part of the present invention, except in so far as the various features thereof may enter into certain combinations hereinafter 60 set forth in the claims, it is thought to be unnecessary to describe the same more in detail.

Adjustably secured to the rock shaft 48, as by means of a set screw 49, is an upwardly 65 projecting arm 50 having a link 51 pivot-

ally connected therewith at one end and at its opposite end to a plate 52, secured as by means of a rivet 53 to a ribbon guide member 54. This ribbon guide member 54 is pivotally mounted upon a rod 55 carried indirectly by the end plates 5 of the carriage and is provided with upwardly extending arms 56 carrying at their upper ends slotted ribbon guides 57, which, in the present case, are shown as carrying a multi-colored ribbon 58.

Extending forwardly from the bed plate 31 is a projection 59 which fits in between the upwardly extending arms 56. It is thus seen that as the carriage reciprocates the rod 55 carried thereby is permitted to have a sliding connection with the ribbon guide member 54, which is held against lateral movement by the projection 59.

Connected with each end of the rod 55 is a horizontally disposed pivotally mounted lever 60 fulcrumed upon a projection 61 carried by each of the end plates of the carriage. The opposite end of the lever 61 is provided with a small hand grip 62 having a central pin on the inner side adapted to engage one of a plurality of holes 63 in the end plate 5 and lock the ribbon in shifted position. In the present case five of these holes are shown, and it is thus seen that by placing the pin in either of the upper holes two paths of impressions may be made in one of the colors of the ribbon, while in the two lower holes two paths may be made in the other. The intermediate hole permits impressions to be made in both colors at the same time.

The operation of this device is substantially as follows: Assume the ribbon to be set in a predetermined position with relation to the printing point, as by means of the adjusting mechanism just described carried by the end plate of the carriage, and the ribbon being fed from one spool to the other through the ribbon guides 57, as shown diagrammatically in Figs. 3 and 4. Whenever the key lever 42 is actuated the universal rock shaft 48 will be turned to carry the upper part of the ribbon guide arm 56 rearward, as shown in Fig. 4, thereby permitting the type carrier 34 to carry the ribbon rearwardly to make an impression upon the paper carried by the platen. As the key lever is released and the members returned to normal position the arms 56 will be carried forwardly, carrying the ribbon therewith in substantially the path of travel of the type carriers, and while still remaining in the path of travel of the type carriers and covering the printing point they nevertheless are moved forward sufficiently to expose the printed matter to the eyes of the operator, which are somewhat above the level of the machine. When it is desired to print capital letters or figures, the proper 12 13

shift key is actuated to carry the platen upwardly or downwardly from the normal position, in the manner heretofore described, which causes a simultaneous shifting movement of the ribbon guide members so as always to maintain the ribbon in the same relative position to the printing point. After the ribbon has been worn by one path of impressions the ribbon adjusting means 10 may be actuated to shift the ribbon guide and change its relation to the printing line, whereby a fresh path on the ribbon may be used. In a similar manner a different color or a multi-colored impression may be made, 15 as desired. The sliding connection between the ribbon guide and the platen carriage upon which the guide is directly mounted permits the carriage to reciprocate in a free and unrestricted manner without changing 20 the position of the ribbon relatively to the type member.

It is thus seen that this invention provides a simple and practical device of the above character adapted to attain, among 25 others, all of the objects and advantages heretofore set forth.

As many changes could be made in the above construction and many apparently widely different embodiments of this invention could be made without departing from the scope thereof, it is intended that all matter contained in the above description or shown in the accompanying drawings shall be interpreted as illustrative and not in a 35 limiting sense.

Having described my invention, what I claim as new and desire to secure by Letters Patent is:—

1. In a typewriting machine, the combination with a reciprocating platen carriage, of a ribbon guide directly connected therewith, and means for holding said guide against movement as said carriage reciprocates.

2. In a visible typewriting machine, the combination with a shiftable longitudinally reciprocating platen carriage, of a ribbon guide pivotally supported from said carriage and shiftable therewith, and means 50 for holding said ribbon guide against movement as said carriage reciprocates.

3. A longitudinally reciprocating carriage, a rod carried thereby, and a ribbon guide mounted on said rod to permit a relative movement therebetween as said carriage reciprocates.

4. A longitudinally reciprocating carriage, a rod carried thereby, a ribbon guide mounted on said rod to permit a relative 60 movement therebetween as said carriage reciprocates, and means for setting said ribbon guide in a predetermined relation to said printing point.

5. A longitudinally reciprocating carriage, a rod carried thereby, a ribbon guide

mounted on said rod to permit a relative movement therebetween as said carriage reciprocates, means for setting said ribbon guide in a predetermined relation to said printing point, and means for locking said ribbon in set position.

6. A longitudinally reciprocating carriage, a rod carried thereby, a ribbon guide mounted on said rod to permit a relative movement therebetween as said carriage reciprocates, and means for shifting said ribbon guide transversely of the printing line for changing the path of impressions thereon.

7. In a typewriting machine, in combination, a platen, a ribbon and ribbon guide normally positioned opposite the printing point, said ribbon guide being pivotally supported intermediate its ends, a link connected with the lower end of said guide for swinging the guide and ribbon relatively to the platen, and means for simultaneously shifting the ribbon guide and platen for printing upper case characters.

8. In a typewriting machine, in combination, a platen, a ribbon and ribbon guide co-acting therewith, said ribbon guide being pivotally supported intermediate its ends, a link connected with the lower end of said guide for swinging the guide and ribbon relatively to the platen, means for shifting the pivotal support of said ribbon guide for changing the relative position between the platen and the ribbon, whereby a different path of impressions is made upon said ribbon, and means for simultaneously shifting the ribbon guide and platen for printing upper case characters.

9. In a typewriting machine, in combination, a platen carriage, a type carrier, means adapted to operate said type carrier to effect printing, ribbon feeding mechanism, means adapted to shift said carriage in a direction transverse to the printing line, a support movable with said carriage, a ribbon guide loosely pivoted on said support so as to be movable transversely of the printing line, and an adjustable hand lever pivotally connected to said ribbon guide and fulcrumed on said carriage.

10. In a typewriting machine, in combination, a platen carriage, a type carrier, means adapted to operate said type carrier to effect printing, ribbon feeding mechanism, means adapted to shift said carriage in a direction transverse to the printing line, a support movable with said carriage, a ribbon guide loosely pivoted on said support so as to be movable toward and from the platen and transversely of the printing line and an adjustable hand lever pivotally connected to said ribbon guide and fulcrumed on said carriage.

11. In a typewriting machine, in combination, a platen carriage, a type carrier,

- means adapted to operate said type carrier to effect printing, ribbon feeding mechanism, means adapted to shift said carriage in a direction transverse to the printing line, a support movable with said carriage, a ribbon guide comprising spaced arms loosely pivoted on said support so as to be movable transversely of the printing line, a stationary member between said arms 5 adapted to prevent lateral movement thereof, and an adjustable hand lever pivotally connected to said ribbon guide and fulcrumed on said carriage.
12. In a typewriting machine, in combination, a platen carriage, a type carrier, means adapted to operate said type carrier to effect printing, ribbon feeding mechanism, means adapted to shift said carriage in a direction transverse to the printing line, a support movable with said carriage, a ribbon guide comprising spaced arms loosely pivoted on said support so as to be movable toward and from the platen, and a stationary member between said arms 10 adapted to prevent lateral movement thereof.
13. In a typewriting machine, in combination, a platen carriage, a type carrier, means adapted to operate said type carrier to effect printing, ribbon feeding mechanism, means adapted to shift said carriage in a direction transverse to the printing line, a support movable with said carriage, a ribbon guide comprising spaced arms loosely pivoted on said support so as to be movable toward and from the platen, and a stationary member between said arms 15 adapted to prevent lateral movement thereof.
14. In a typewriting machine, in combination, a part shiftable to permit different case printing, a pivotally mounted ribbon guide movable about its axis toward and from the printing point, and a pivotally mounted support for said guide shiftable with said part and movable about its axis to adjust said guide transversely to the 20 printing line.
15. In a front strike typewriting machine, the combination of a pivoted vibratory ribbon carrier, means for moving said carrier toward and away from the platen substantially radially thereof at printing operation, said carrier normally leaving the printing face of the platen uncovered, and hand controlled means for pivotally moving said carrier up or down to one or another of a plurality of predetermined normal positions.
- In testimony whereof I affix my signature, in the presence of two witnesses.
- WELLINGTON PARKER KIDDEE.
- Witnesses:
- R. S. BARROWS,
K. M. KNUCKEN.

- means adapted to operate said type carrier to effect printing, ribbon feeding mechanism, means adapted to shift said carriage in a direction transverse to the printing line, a support movable with said carriage, a ribbon guide comprising spaced arms loosely pivoted on said support so as to be movable transversely of the printing line, a stationary member between said arms 5 adapted to prevent lateral movement thereof, and an adjustable hand lever pivotally connected to said ribbon guide and fulcrumed on said carriage.
12. In a typewriting machine, in combination, a platen carriage, a type carrier, means adapted to operate said type carrier to effect printing, ribbon feeding mechanism, means adapted to shift said carriage in a direction transverse to the printing line, a support movable with said carriage, a ribbon guide comprising spaced arms loosely pivoted on said support so as to be movable toward and from the platen, and a stationary member between said arms 10 adapted to prevent lateral movement thereof.
13. In a typewriting machine, in combination, a platen carriage, a type carrier, means adapted to operate said type carrier to effect printing, ribbon feeding mechanism, means adapted to shift said carriage in a direction transverse to the printing line, a support movable with said carriage, a ribbon guide comprising spaced arms loosely pivoted on said support so as to be movable toward and from the platen, and a stationary member between said arms 15 adapted to prevent lateral movement thereof.
14. In a typewriting machine, in combination, a part shiftable to permit different case printing, a pivotally mounted ribbon guide movable about its axis toward and from the printing point, and a pivotally mounted support for said guide shiftable with said part and movable about its axis to adjust said guide transversely to the printing line.
15. In a front strike typewriting machine, the combination of a pivoted vibratory ribbon carrier, means for moving said carrier toward and away from the platen substantially radially thereof at printing operation, said carrier normally leaving the printing face of the platen uncovered, and hand controlled means for pivotally moving said carrier up or down to one or another of a plurality of predetermined normal positions.

In testimony whereof I affix my signature, in the presence of two witnesses.

Corrections in Letters Patent No. 1,194,845.

It is hereby certified that in Letters Patent No. 1,194,845, granted August 15, 1916, upon the application of Wellington Parker Kidder, of Boston, Massachusetts, for an improvement in "Type-Writing Machines," errors appear in the printed specification requiring correction as follows: Page 2, line 70, after the article "a" insert the words *support or*; same page, line 78, after the article "a" insert the words *stationary member or*; and that the said Letters Patent should be read with these corrections therein that the same may conform to the record of the case in the Patent Office.

Signed and sealed this 19th day of September, A. D., 1916.

[SEAL.]
